METHOD FOR TREATING COILED BODIES

Ernst A. Nördberg, Southport, Conn.

Application July 11, 1945, Serial No. 604,333

4 Claims. (Cl. 242—55)

1

My present invention relates generally to the treatment of coiled bodies such as capacitor windings, and has particular reference to an improved method for improving the structure of such bodies.

The invention is primarily directed, from one aspect, to the manufacture of electrical condensers or equivalent devices composed of spirally-interwound alternately arranged conductive and dielectric layers; and it is a general object to provide a method and means for improving the physical structure of such bodies, thereby achieving a number of advantages among which are an increase in staunchness, greater compactness, higher efficiency and better economy in manufacture, and a reduction in the likelihood of premature electric break-down. Accordingly, I have herein illustrated and shall hereinafter describe the invention from the standpoint of its special utility in this specific art, but it will be understood that certain phases of my invention are not necessarily restricted to capacitor windings and may find applicability in other fields.

As is well-known, there is a type of capacitor which is formed by superposing in appropriate sequence a series of conductive strips, such as metallic foil or the like, and dielectric strips, such as paper or the like, and winding these strips in spiral fashion to form a coiled body of substantially cylindrical shape, this body being subsequently subjected to suitable heat and vacuum treatment, and to impregnation with, or immersion in, a suitable dielectric material such as wax, oil, or the like. Conductive terminals are suitably associated with the conductive coils of the wound body, and the entire device is ultimately encased in a suitable enclosure or container on which the terminals are accessible. During the course of manufacture the body may or may not be flattened.

Where a body of this kind is wound on an arbor, as is customary, the space occupied by the arbor or by its component parts leaves a hole or gap in the axial region of the body when the latter is removed. As a result, the body has an inherent physical weakness in this region, regardless of the degree of tightness with which the strips may have been wound, which imparts to the body an undesirable softness, looseness, and deformability.

In an attempt to overcome this difficulty, it is customary practice to squeeze the body quite deliberately into a flattened compacted condition before or during the impregnation procedure. However, it is often desirable that the body be caused to retain a substantially cylindrical contour, and in such a case the handling of the body

5 and the performance of the impregnation and other procedures incidental to the final completion of the desired capacitor is beset with a special difficulty arising from the fact that the strips adjacent to the core are relatively loose and unsupported after the body has been removed from the arbor. This condition is conducive to a shifting, maladjustment, or further loosening of the strips which may deleteriously affect the life of the capacitor or may even destroy completely the usefulness of the wound body for the intended purpose.

By means of my present invention, I am enabled to provide a body of the character described, 15 which is substantially cylindrical, yet tightly wound throughout, and completely devoid of any "arbor hole"; and this desirable result is achieved without abandoning the ordinary and basic procedure involving the use of a conventional winding arbor as a rotating support upon which the various conductive and dielectric strips are initially coiled.

20 A characterizing feature of my invention resides in the special treatment to which the coiled body is subjected immediately after its removal or separation from the winding arbor. Briefly stated, this treatment consists in subjecting the body to a twirling action about its own axis and in the direction which coils the body more tightly. 25 This compacting action is effected by the application to the peripheral surface of the body of tangential forces which induce the twirl, coupled with a continuous inwardly-radial pressure which gradually reduces the volume of the body.

30 I achieve the foregoing general objects and advantages, and such other objects and advantages as may hereinafter appear or be pointed out, in the manner illustratively exemplified in the accompanying drawings in which:

35 Figure 1 is a longitudinal view of an apparatus by means of which the invention may be practised;

Figure 2 is a cross-sectional view showing an illustrative drive mechanism; and

40 Figure 3 is an exaggerated cross-sectional view through a conventional type of winding arbor at the commencement of an ordinary winding operation.

45 For illustrative purposes, I have shown in Figure 3 the two cooperable parts 10 and 11 of a winding arbor of the well-known "split mandrel" type. I have shown the manner in which an ordinary winding procedure brings a plurality of superposed strips into threaded engagement with this arbor, and the manner in which this winding

is initiated. While the strips may be assembled with varying numbers of layers or plies, and in various successive arrangements appropriate to the particular type of wound body which is desired, I have chosen to illustrate for explanatory purposes a typical assembly of six strips 12-17. The strips 13 and 16 are composed of conductive material such as foil. Each of these strips is sandwiched between a pair of dielectric strips composed of paper or the like, the foil strip 13 being sandwiched between the paper layers 12 and 14, and the foil strip 16 being sandwiched between the paper layers 15 and 17. In initially bringing this group of layers into superposed relationship, the strips are laid one upon the other so that the paper or non-conductive layers project beyond the ends of the foil or conductive layers. This is to assure a condition of electrical insulation between the conductive strips 13 and 16 at the core of the ultimate wound body. After the strips have been brought into desired superposed relationship, they are threaded into engagement with the arbor. In the case of a split mandrel of the character shown, this involves the insertion of the strips into and through the space between the two portions 10 and 11. The arbor or mandrel is then rotated in the direction of the arrow 18, and this initiates a winding of the strips into a coiled body 21. After the desired lengths of strips have been wound, they are cut off at their outer ends in a manner which is not illustrated in the present drawings, with the paper layers having their ends projecting beyond the outer ends of the foil layers, thus electrically shielding the outer ends of the foil layers from each other. The wound body is then removed from the arbor. In the case of a split mandrel of the character shown, this procedure is facilitated by the longitudinal withdrawal of one of the mandrel sections 10, 11, prior to the similar withdrawal of the other.

The substantially cylindrical body which is thus produced has one or more gaps or spaces in its axial region. For the sake of convenience, these gaps have been shown in Figure 1 as a single axial opening 19, and may be designated collectively as a "hole."

In ordinary commercial practice, a sticker or label is immediately applied to the peripheral surface of the wound body so as to retain the strips in wound condition, and the body is then subjected to the usual heat and vacuum and impregnation treatments. Prior to or during these procedures, it may be flattened by a slight pressure, thus squeezing the body into a compacted shape of substantially elliptical cross-section, or the initial substantially cylindrical shape may be retained.

In accordance with my present invention, however, the wound body 21, as it is removed from the winding arbor, is not yet ready for the application of the conventional sticker or label, and is introduced, as indicated by the arrow 20, into a suitable apparatus by means of which the present special treatment is performed.

There are winding arbors in common usage which are slightly different from the "split mandrel" construction shown in Figure 3, but in each case, the presence of the arbor or its component parts always results in the provision of an axial hole as indicated at 19 in Figure 1. It will therefore be understood that the diagrammatic showing of Figure 3 is purely illustrative to explain the presence of the hole 19 in the wound body 21, and that the invention is applicable to any arbor-wound body which is characterized by the fact

that it is substantially cylindrical, that it has an axial space or hole 19, and that it is composed of spirally-wound strips, the outer ends of which are illustratively shown at the left of Figure 1 and designated by the reference numeral 22.

The method steps of the present invention may be carried out in a variety of ways, and the apparatus shown in Figures 1 and 2 is merely an illustrative preferred structure which has proven satisfactory for the present purpose. It consists of two continuous belts 23 and 24. The belt 23 extends around the pulleys 25 and 26, while the belt 24 extends around similar pulleys 27 and 28, these pulleys being so arranged that each belt has a span arranged substantially in a plane, these spans being juxtaposed in spaced substantially parallel relationship. By means of a suitable mechanism, such as that which is shown in Figure 2, the span portion of the belt 23 is caused to move longitudinally in the direction of the arrow 29, while the opposed span portion of the belt 24 is caused to be moved in the opposite direction as shown by the arrow 30. The belt 23, however, is caused to have a lineal speed greater than that of the belt 24. Each of the belts has an outer portion formed of relatively soft and yieldable yet resilient material, such as rubber or the like. I have illustratively shown each belt formed of a backing 31 (see Figure 2) of canvas or the like, and an outer operative portion 32 of resilient material of the character mentioned.

Associated with the belt 23, between the pulleys 25 and 26, is a rigid panel 33 over which the operative span of the belt travels. A similar rigid panel 34 is mounted between the pulleys 27 and 28 to serve as a backing over which the operative span of the belt 24 travels. The panels 33 and 34 may be mounted on a convenient supporting structure 35 (Figure 2) which supports at least one pair of the belt pulleys, as well as the driving mechanism.

Before describing the operation of the apparatus and the features of the present method and procedure, attention is directed to Figure 2 in which I have shown one illustrative way of driving the belts 23 and 24 in the desired relationship. The pulley 25 may be mounted, for example, on a shaft 36 which is journaled in the supporting structure 35 and which carries a pinion or gear 37. An intermediate pinion 40 may be mounted on a jack shaft 41. The shaft 38 may serve as the driving shaft, connected (in a manner not shown) to a suitable source of power such as an electric motor or the like. The interconnection of the gears 39, 40 and 37, brings about a rotation of both pulleys 25 and 27 when the driving shaft 38 is rotated. Where this driving mechanism is associated with the pulleys 25 and 27 as indicated for illustrative purposes, the other pulleys 26 and 28 (at the right of Figure 1) may be mounted in any convenient manner to serve merely as idler or guiding pulleys.

By making the gear 37 slightly smaller in diameter than the gear 39, the lineal speed of the belt 23 may be caused to be slightly greater than that of the belt 24, as hereinbefore mentioned.

Reverting now to the arbor-wound coiled body 21: this body is introduced at the region 20 to the action of the cooperating belts 23 and 24. It is introduced in the relationship shown in Figure 1, its axis being transverse with respect to the operative portion of the belts, and the free ends of the strips of which it is composed being arranged as shown at 22 in Figure 1. The greater lineal speed of the belt 23 causes this body to be

immediately engaged by the two belts, in an interposed relationship between the operative span portions of the belts. As a result, the body advances slowly and presently assumes a position such as that indicated by the reference numeral 42. Ultimately, the body advances completely through the apparatus to a discharge point as indicated by the arrow 43. Intermediate positions of the body are illustratively shown at 44 and 45.

As will be observed, the outer portions of the two belts serve as pressure surfaces adapted frictionally to engage the body 21 on its peripheral surface, the regions of engagement being substantially diametrically opposed. The yieldable resilient nature of these pressure surfaces causes them to engage the coiled body frictionally, and to impart tangential forces to the body, as well as an inwardly-radial pressure. The tangential forces impart a twirl to the body in the direction which winds the body more tightly about its axis. At the same time, the continuous radial pressure induces the body gradually to reduce its volume. The result is indicated by comparing the bodies designated by the reference numerals 42, 44 and 45. When the body is introduced to the action of the belts or pressure surfaces, it has a relatively large initial external diameter. As it twirls on its axis, under the influence of the frictional force applied by the pressure surfaces, and as these pressure surfaces continuously exert an inwardly-radial pressure upon it, this external diameter gradually decreases, and at the same time, the hole 19 gradually diminishes in size until the body ultimately leaves the apparatus in a relatively compacted condition. In this condition, it is still substantially cylindrical in shape, the strips of which it is composed are still in the desired relationships to one another, yet the arbor hole 19 has been completely eliminated. The body is therefore substantially rigid and compact, and after a sticker or the like has been applied to its outer surface, to hold the outer ends of the strips in position, the body lends itself readily to further handling and treatment, without any danger of maladjustment of the component strips.

Bodies may be subjected to the action of the apparatus in a continuous and successive manner, and the showing of Figure 1 might be construed, if desired, to represent four separate coiled bodies under simultaneous treatment. That is, the reference numeral 45 might be construed as designating a body which is just ready to leave the apparatus in compacted condition, the reference numerals 42 and 44 might be deemed to designate two other bodies which are in process of being treated, and the reference numeral 21 may be deemed to represent a body at the instant of its introduction to the action of the apparatus.

Obviously, bodies of any size may be treated, it being understood that the spacing of the operative portions of the belts will always be adjusted to accommodate a predetermined range of sizes. The operative spans of the belts may be of any desired longitudinal extent, and the lineal speeds at which the belts travel may be adjusted to suit varying requirements.

Under certain circumstances, the two opposed pressure surfaces may be constructed otherwise than as portions of two belts. For example, one of the pressure surfaces might be a stationary element while the other pressure surface travels. To conserve space, however, it is preferable that

both belts be caused to move, with one belt having a slightly greater lineal speed. This results in subjecting the wound body to the twirling and pressure action of the pressure surfaces for a maximum period of time within a minimum amount of space.

The tightly-wound bodies resulting from the present treatment are particularly well adapted to form condenser devices or the like in which the body is embedded or molded within an enclosure of plastic or the like. In fact, the compacted body is in an admirable structural state for handling and mounting in any convenient or desired type of ultimate enclosure. Its compact and rigid nature minimizes the likelihood of undesirable shifting of the foil and paper strips at the core of the body, as a result of which there is a minimum of loss during the manufacturing process, due to defectively-wound bodies, and a minimum likelihood that the completed capacitors or equivalent devices will prematurely break down electrically.

Having thus described my invention and illustrated its use, what I claim as new and desire to secure by Letters Patent is:

1. The method of treating a coiled arbor-wound condenser body, which consists in twirling the body on its axis and simultaneously exerting a continuous inwardly-radial pressure upon its peripheral surface, said twirl being in the direction which coils the body more tightly about its axis.
2. The method of treating a coiled arbor-wound condenser body, which consists in twirling the body on its axis and simultaneously exerting a continuous inwardly-radial pressure upon its peripheral surface, said twirl being in the direction which coils the body more tightly about its axis, and said pressure being exerted from points in substantially diametric opposition to each other.
3. The method of making a tightly-wound coiled condenser body composed of alternate conductive and dielectric layers, which consists in winding a series of conductive and dielectric strips in appropriate superposed relation upon an arbor, removing the wound body from the arbor, and then twirling the body on its axis and simultaneously exerting a continuous inwardly-radial pressure upon its peripheral surface, said twirl being in the direction which coils the body more tightly about its axis.
4. In the art of making an electrostatic condenser of the character described, the procedure which consists in frictionally engaging the peripheral surface of a spirally-coiled body at substantially diametrically opposite regions, and subjecting said body at said regions to oppositely-directed tangential forces and to an inwardly-radial pressure, said tangential forces being applied in directions which impart to the body a volume-reducing twirl which coils the body more tightly about its axis.
